(57) **CLAIM**

The ornamental design for a microphone boom cover, as
shown and described.

DESCRIPTION

FIG. 1 is a front elevational view of a microphone boom
cover in accordance with my new design;

FIG. 2 is a rear elevational view of the microphone boom
cover of FIG. 1;

FIG. 3 is a top plan view of the microphone boom cover of
FIG. 1, the bottom plan view being a mirror image thereof;
FIG. 4 is a right side elevational view of the microphone
boom cover of FIG. 1;

FIG. 5 is a left side elevational view of the microphone
boom cover of FIG. 1; and,

FIG. 6 is a rear perspective view of the microphone boom
cover of FIG. 1.
